UNIVERSAL MOTOR SPEED GOVERNOR

Stanley H. Swarthout, Rochester, N. Y., assignor
to General Motors Corporation, Detroit, Mich.,
a corporation of Delaware

Application June 23, 1938, Serial No. 215,426

3 Claims. (Cl. 171—312)

This invention relates to a universal electric motor, that is, a motor which will work either on alternating current or direct current circuits. More particularly the invention relates to a speed 5 governor for universal electric motors.

The present invention is applicable to speed governors of the make and break contact type and is particularly useful on governors where the contact separation or the wiping action of the contact is small. Under these conditions and where close regulation of the speed is required it will be seen that the space between the contacts must be maintained. It is well known that on contacts interrupting a direct current circuit the positive 10 contact is liable to form a crater or pit and the negative contact will in turn build up in the form of a cone or needle or other shape, this action being progressive. On contacts interrupting an alternating current circuit, since the current is reversed every half cycle, there is no chance for either contact to build up or pit and consequently both contacts wear down evenly. The pitting of the one contact and the building up on the other which ordinarily occurs with direct current use 15 may seriously affect the regulation of the motor speed; therefore, it is very desirable to eliminate the transfer of material between the contacts to obtain uniform and equal wear on both contacts.

The object of the present invention is to provide means for obtaining uniform wear of the contacts on a speed governor or motor regardless of whether it is used on direct or alternating current.

Further objects and advantages of the present 20 invention will be apparent from the following description, reference being had to the accompanying drawing wherein a preferred embodiment of the present invention is clearly shown.

The figure of the drawing is a wiring diagram 25 embodying the present invention.

One application of the electric motor embodying the present invention is to drive a direct current generator for supplying current to the power amplifier of a motion picture outfit which incorporates sound effects. As the motor circuit embodying the present invention is capable of other uses the particular load which is applied to the motor is not shown in the figure of the drawing.

In the drawing 20 designates a universal motor 30 of the series type having one of its brushes 21 connected with the series field winding 23 which is connected with line wire 24. The motor armature shaft 25 drives a disk 30 on one side of which are mounted two speed-responsive circuit breakers 31 and 32, which are similar in construction.

Circuit breaker 31 comprises a relatively stationary contact 33 cooperating with a relatively movable contact 34. Contact 33 is mounted on a plate 35 supported by leaf spring 36 attached to a bracket 37, which is insulatingly supported by the disk 30. Contact 34 is attached to a pair of plates 38 supported upon a leaf spring 39 attached to a bracket 40 which is insulatingly supported by the disk 30. The plates 38 serve as a weight which is affected by centrifugal force to cause it to move outwardly from the shaft 25 so as to separate the contact 34 from the contact 33 at a predetermined speed. Spring 39 biases contact 34 into closed position. The speed at which contact 34 separates from contact 33 is varied by varying the tension in spring 39 which is controlled by a set screw 41 mounted on a bracket 42 insulatingly supported by the disk 30.

The other circuit breaker 32 has contacts 43 and 44 corresponding, respectively, to contacts 33 and 34 of breaker 31. The parts of the breaker 32 supporting contacts 33 and 34 have been identified by reference numbers which are the same as the reference numbers applied to the corresponding parts of the breaker 31, except that the letter "a" is affixed.

The contacts of the circuit breakers 31 and 32 are connected with a commutating device located on the reverse side of the disk 30. The commutating device comprises an outer split ring including the parts K and L, a continuous collector ring N and a continuous collector ring U. The contacts 33 and 34 of breaker 31, which will hereinafter be known as contacts O, are connected with the split connector rings K and L by wires 53 and 54 respectively. The contacts 43 and 44 of breaker 30, which will hereinafter be known as contacts P, are connected by wires 63 and 64 respectively with continuous collector rings Q and N. The frame of the electric motor insulatingly supports 35

brushes 70 and 71 which bear upon the half rings K and L, a brush 72 which bears on the ring N and 40

a brush 73 which bears on the ring Q. The ring parts K, L, N and Q are insulatingly supported 45

by the disk 30. The ends of the ring parts K and L are provided with tungsten inserts T.

The brush 70 is connected by wire 74 with wire 75 which is connected between brush 72 and motor 50

commutator brush 22; brush 70 is also connected by wire 76 with a resistor I which is connected by 55

wire 77 with line wire 26. A condenser H is in shunt with resistor I. Brush 71 is connected by wire 78 with a contact D. Brush 73 is connected by wire 79 with a contact E. The contacts D and 55

E are parts of a relay which include also a double

contact C mounted on an armature 80 pivoted at 81 and urged in a clockwise direction by a spring 82, one end of which is fixed with armature 80 and the other with a stationary part 83. The relay 5 includes an electromagnet B, the winding of which is connected to line wire 26 and the other end of which is connected through a condenser F to a line wire 24. It will be observed since magnet winding B is connected only by capacity F with line wire 24 the relay will operate only on alternating current applied to the line wires 24 and 26.

When direct current is applied to the wires 24 and 26 current flows through the following circuit: wire 24, motor field winding 23, armature of the motor, wire 15, wire 14 to the brush 10, contacts O, collector ring L, brush 11, wire 18, contact D contact C, armature 80 and line wire 26. The contacts O, including parts 33 and 34 15 are shunted by the condenser H through the following circuit: condenser H, wire 16, brush 10, ring segment K, wire 53, contacts O, wire 54, ring segment L, brush 11, wire 18, contact D, contact C, armature 80, wire 26, wire 17, condenser H.

When operating the motor on direct current, 25 the speed is regulated by the contacts O. When the speed has attained a certain value, the centrifugal force applied to the weight 38 will overcome the bias of the spring 39, thereby causing the contact 34 (of the pair of contacts O) to be separated from the contact 33. Since these contacts O are in series with the electric motor as previously explained, the operation of the motor will be affected by the opening of the contacts O, 30 whereby the motor speed will decrease; and then, when the speed has decreased to a certain value the contacts O will close again. In this way the speed is regulated by the speed-responsive circuit breaker 31. The resistor I, which like the condenser H is in shunt to the contacts O, is of a suitable value for preventing the motor circuit from being interrupted when the contacts are open, while not affecting the speed of regulation. The resistor I reduces sparking at the contacts O and is assisted by the condenser H in this function. 35

In describing the circuits which function during direct current operation of the motor the description has been given as though the commutating segments K and L were stationary. Obviously 50 their position is reversed every half revolution of the motor shaft. Therefore, every half revolution the direction of the current flow through the contacts O is reversed. In this way the transfer of material across the contacts in one direction is compensated for by practically equal transfer of the material between the contacts in the opposite direction. Then the tendency for the contacts to build up or pit is practically eliminated.

When alternating current is applied to the line 55 wires 24 and 26 current flows through the condenser F and the relay winding B. Hence, the armature 80 is attracted toward the magnet and opens the circuit between C and D and closes the circuit between C and E. Therefore, the following 60 circuit is operative during which alternating current is applied to the line wire: line wire 24, motor field winding 23, armature of the motor, wire 15, brush 12, commutating ring N, wire 64, contacts P wire 63, commutating ring Q, brush 13, wire 18, contact E, contact C, armature 80 and line wire 26. It will then be seen that, when 65 alternating current is applied to the line wires 24 and 26, the continuous collector rings N and

Q and the governor contacts P are used. These contacts P function to regulate the motor speed when operating on alternating current in the same manner as the contacts O function to regulate the motor speed when operating on direct current. The condenser H and the resistor I are also shunted across the contacts P through the following circuit: wire 16, brush 10, wire 14, wire 15, brush 12, collector ring N, wire 64, contacts P, wire 63, ring Q, brush 13, wire 19, contact E, 10 contact C, armature 80, wire 26 and wire 17 back to the condenser H and resistor I. The condenser H and resistor I function to reduce sparking at the contacts E.

It has been found that, in order to obtain the 15 desired operating life from the governor, the split collector rings K and L can not be used for alternating current operation on a 110 volt circuit and that the continuous collector rings N and Q must be used.

It is apparent from the foregoing description of the construction and mode of operation of the governor circuits, embodied in the present invention, that there has been provided a motor with a speed governor in which very close speed regulation can be obtained and maintained over long periods of operation regardless of whether the motor is operated upon alternating or direct current.

While the embodiment of the present invention 30 as herein disclosed, constitutes a preferred form, it is to be understood that other forms might be adopted, all coming within the scope of the claims which follow.

What is claimed is as follows:

1. A control circuit for universal motors comprising, in combination, two speed responsive circuit breakers driven by the motor, means for automatically selectively connecting one or the other of said circuit breakers in circuit with the motor depending on whether the motor operates on direct current or on alternating current, whereby the motor speed will be regulated when the motor operates on either kind of current, and means for automatically reversing polarity through the contacts of that speed responsive circuit breaker which regulates the speed of the motor when operating on direct current. 35

2. A control circuit according to claim 1 in which the automatic selecting means comprises an electromagnet relay having an armature normally biased to complete the circuit of the electric motor through the circuit breaker which controls motor speed for direct current operation and having an electro-magnet winding capacity-coupled across the line so as to be energized by alternating current only, the energizing of the electromagnet by alternating current causing the armature to disconnect the D. C. circuit breaker for controlling speed, and to connect the A. C. circuit breaker for controlling speed. 40

3. A control circuit according to claim 1 in which the means for automatically reversing polarity through the contacts of the speed responsive circuit breaker which regulates motor speed when operating on direct current comprises a motor-driven bi-segmental, split collector ring having its segments connected respectively with said contacts and mounted, and brushes cooperating with the split ring for connecting the segments with the motor and line, the polarity through the segments being automatically reversed by the motor. 45
